TELLTALE HOLE OPENER FOR STAYBOLTS

Edward S. Fitz Simmons, Library, Pa., assignor
to Flannery Bolt Company, Bridgeville, Pa., a
corporation of Delaware

Application August 24, 1940, Serial No. 354,052

1 Claim. (Cl. 121—10)

This invention relates to a device for cleaning out the holes of tell-tale staybolts prior to testing during the inspection of boilers in which the bolts are installed.

Staybolts with tell-tale holes therethrough are well-known and have been widely used for many years in the construction of locomotive boilers. When boilers constructed with such staybolts are to be inspected, it is necessary to make sure that the tell-tale holes are open and free from obstruction throughout their entire length. The clogging of the tell-tale holes in the staybolts by the accumulation of material therein is almost impossible to prevent under some operating conditions, despite the insertion of porous plugs in the open ends of the holes which is customary. The accumulated material, furthermore, may be of such character that it is very difficult to remove. Sometimes the accumulations have a flinty hardness such that tools heretofore available will not suffice to loosen them.

I have invented a device for clearing the tell-tale holes of staybolts, which is capable of removing even the hardest deposit since it utilizes both impact or percussion and cutting edges for reducing the accumulations to the form in which they may be readily removed. In a preferred embodiment, the invention comprises a pneumatic gun having a piston reciprocable therein adapted to serve as a hammer. A drill, of such size as to be insertable in the tell-tale hole of a staybolt, has a head rotatably received in the end of the gun in such position as to be subject to the impact of the reciprocating piston. The drill is yieldably held in position in the gun and is provided with means whereby it may be manually rotated relative to the gun. The drill has a passage extending longitudinally throughout the length thereof and the piston also has a central bore whereby the motive fluid, usually compressed air, is delivered to the end of the drill to blow out particles of material accumulated in the tell-tale hole, as it is granulated by the combined effect of the hammer blows applied to the drill and the engagement of its cutting edges with such accumulations.

The accompanying drawings illustrating a preferred embodiment of the invention, will be referred to during the following detailed description and explanation. In the drawings:

Fig. 1 is a longitudinal, central, sectional view illustrating the invention, with parts in elevation;

Fig. 2 is a view similar to Fig. 1 showing parts in alternative positions;

Fig. 3 is a view partly in section along the plane of line III—III of Fig. 1 and partly in elevation;

Fig. 4 is an end view of the drill; and

Fig. 5 is a central, longitudinal section through a tell-tale hole staybolt installed in a boiler, illustrating the use of the invention in removing the material which accumulates therein during normal operation.

Referring now in detail to the drawings, the device of my invention comprises a gun 10 and a drill 11. As to most of its features, the gun 10 is of known construction and will, therefore, be described rather generally for the most part, and the detailed description confined to the novel features. The gun 10 includes a handle 12 and a barrel 13. The barrel 13 is threaded into a bore 14 in one end of the handle and is provided with a valve case 15 and a plug 16 closing the rear end of the valve case. A dowel pin 16a maintains the valve case 15 and the plug 16 in the proper angular relation relative to the barrel 13.

The barrel 13 has a longitudinal bore 17 therethrough in which a piston 18 is reciprocable. The bore 17 is slightly enlarged at each end as indicated at 19 and 20. A restricted passage 21 provides communication between the bore 14 and the enlargement 19. A passage 22 extends from the bore 14 longitudinally of the handle 12 and communicates with a supply of motive fluid such as compressed air, by a connection 23. A throttle valve 24 actuated by a push button 25 controls the supply of air to the passage 22.

The valve case 15 has a bore 26 in which a sleeve valve 27 is reciprocable. As shown in the drawings, the valve 27 has a longitudinal bore 28 through which the piston 18 reciprocates. The bore 28 has a substantially central enlargement 29, is provided at the rear end of bore 32. The valve case 15 has a passage 30 formed therein which communicates with a recess 30a in the forward face of the plug 16. A passage 31 extends forwardly from the bore 14 into the valve case 15 and plug 16.

As shown in Fig. 1, the rear end of the valve 27 reciprocates in a bore 32 in the plug 16. An annular groove or enlargement 33 is formed in the bore 32 and is in communication, through passages 34, with the bore 14.

The valve 27 is turned down slightly adjacent the rear face of the central shoulder thereof forming a groove 34a. The groove 34a connects the recess 30a to a passage 31a intersecting passage 31, when the valve is in its rear position as shown in Fig. 1.

A radial exhaust passage 35 formed in the barrel 13 intersects the bore 32 and is open to the atmosphere. A passage 36 through the valve case 15 and barrel 13 extends to the enlargement 20 at the forward end of the bore 17, and is in communication with the passage 30. A similar exhaust passage 35a is spaced rearwardly from the passage 35.

The structure described so far operates in the known manner to reciprocate the piston 18 between opposite ends of the bore 17. The piston 18 executes a rapid forward traverse movement which is unchecked, so that it is able to deliver a heavy blow. The forward stroke of the piston is accompanied by a movement of the sleeve valve 27 whereby air under reduced pressure is supplied through the passage 36. This causes the piston to execute a relatively slow return stroke which is checked by the entrapment of air in the rear end of the bore 17 whereby the piston is brought gradually to rest as the entrapped air is discharged through the restricted passage 21. A more detailed description of the operation of the gun follows.

Assuming the moving parts to occupy the relative positions illustrated in Fig. 1, i. e., the piston 18 near the forward end of the bore 17 and the valve 27 in its rearmost position, air under pressure is admitted to the passage 22 and bore 14 when the valve 24 is opened by actuating the push button 25. From the bore 14, air flows through the passage 31, the passage 31a, around the groove 34a, through the recess 30a, passages 30 and 36 to the forward end of the bore 17. The piston 18 is forced rearwardly as the pressure builds up in the forward end of the bore 17.

After traversing a portion of its rearward stroke, the piston 18 uncovers a radial port 35b in the barrel 13. A longitudinal passage 36a in the barrel intersects the port 35b and communicates with a passage 36b in the valve case 15. A restricted port 36c connects the passage 36b to the passage 31. When the port 35b is uncovered, air under pressure is admitted through the passages just described to the bore 26 and bears on the forward face of the simple flange of the valve to hold it in rear position.

As the piston 18 continues to travel rearwardly, the air displaced ahead of it flows to the atmosphere through the exhaust passage 35. This passage, however, is shortly covered by the piston and the pressure of the air trapped in the rear end of the bore 17 thereupon becomes effective upon the rear annular surface of the valve adjacent the enlargement 29 tending to move it forward as soon as the trailing end of the piston uncovers the passage 35, relieving the pressure behind the piston and ahead of the central shoulder of the valve. As soon as the valve 27 starts forward, air under pressure bears on the rear face of the central shoulder thereof, being supplied through the passages 31 and 31a.

When the valve has moved to the forward position shown in Fig. 2, it closes the exhaust passage 35. The final portion of the rearward stroke of the piston is cushioned by the air trapped in the bore 17, as already described. As a matter of fact, the air in the rear end of the bore 17 is at working pressure because of the connection between the bore and the chamber 14 which is established through the passages 21.

With the valve in the forward position, the supply of air under working pressure to the forward end of the bore 17 is cut off by the blocking

of the passage 31a. The forward end of the bore 17, furthermore, is open to the atmosphere through passages 36 and 30, the recess 30a, the groove 34a and the radial exhaust passage 35a. As previously stated, air under working pressure is effective continuously through the restricted connection 21 to force the piston forward. When the piston on its forward stroke has covered the radial port 35b, the air previously flowing through a restricted port 36c is diverted to the valve case and acts upon the forward face of the central shoulder of the valve causing it to return to its rearmost position. This cuts off the flow of air into the bore 17 through the passages 34 and 15 connects the interior of the bore 17 to the atmosphere through the passage 35. The piston 18 continues to move toward the forward end of the bore by virtue of its momentum and delivers a sharp blow to the drill head, to be described in detail shortly. Simultaneously, air under working pressure is admitted to the forward end of the bore 17 as previously described.

The drill 11 has a head 37, the extreme end 38 of which is turned down to fit rotatably in a bore 39 formed in the forward end of the barrel 13. The head 37 is yieldably held in the position shown in Fig. 1 by a coil spring 40, the outer end of which is contracted around the head and the inner end of which is threaded on the end 30 of the barrel 13 which has a helical groove 41 providing threads to receive the turns of the spring 40. With the head 37 in the position shown, the inner end 38 thereof is in position to receive the impact of the piston 18 when it reaches the end of its forward stroke causing slight relative movement axially between the barrel 13 and the drill 11.

The forward end of the head 37 is preferably provided with flats 42. A lever-type wrench 43 has an opening corresponding in shape with the section of the forward end of the head whereby the drill 11 may readily be turned manually without shifting the handle 12 of the gun.

The shank of the drill 11 indicated at 44 is preferably of tool steel and is shaped at its extreme end to provide cutting edges 45. The drill shank may conveniently be brazed to the head 37. The latter and the piston 18 are preferably of steel and are specially treated to render them very hard and resistant to deformation by impact.

The piston 18 is provided with a central bore or passage 47. The drill 11 is provided with a similar bore 48 extending through the entire length thereof from the extreme rear end 38 through the head 37 and the shank 44 to the working end whereon the cutting edges 45 are formed. The function of these passages will be explained shortly.

The manner of using the tool described above in cleaning out the tell-tale holes of staybolts will doubtless be readily apparent but will be briefly described nevertheless, with reference to Fig. 5. As there shown, a staybolt 46 has a tell-tale hole 46a extending thereto. The bolt has an enlarged head 49 engaging a bearing seat 49a welded to the outer boiler sheet 50. A plug 51 is threaded into the end of the bearing seat. The other end of the bolt is threaded into the inner boiler sheet or fire-box end 52 and is upset as at 53.

In normal operation of a boiler, an accumulation of material such as indicated at 54 tends to build up in the tell-tale hole 46a and this accumulation must be removed before the boiler

may be tested during inspection. To accomplish this removal, the device shown in Fig. 1 is so manipulated as to insert the drill 11 into the open end of the tell-tale hole. The operator then actuates the push button 25 and simultaneously applies pressure to handle 12 to force the cutting edges 45 of the drill into engagement with the accumulated material 54. The resulting reciprocation of the piston 18 delivers heavy blows in rapid succession to the rear end 38 of the head 37 of the drill 11. While forcing the drill into a tell-tale hole with his right hand, the operator manipulates the wrench 43 with his left hand to turn the drill back and forth through a considerable angle as indicated by the chain-lines in Fig. 3. This, of course, has the effect of rotating the drill 11 relative to the gun 10. The rapid blows on the drill combined with the cutting action of the edges 45 thereof effects a rapid granulation of the accumulated material 54. The particles of accumulated material are forced out of the tell-tale hole beyond the working end of the drill by air flowing through the bore 47 in the piston 18 and through the bore 48 through the drill 11. The velocity under which the air flows from the working end of the drill varies from a minimum when the piston is in its rear-most position as shown in Fig. 2, to a maximum just before the piston engages the rear end 38 of the drill head 37. At such time, substantially full line pressure is effective on the rear face of the piston and, since the passages 47 and 48 are in alinement, air flows out through the end of the drill at high velocity. Air is thus delivered from the end of the drill in a series of puffs or jets of maximum velocity in synchronism with the reciprocation of the piston, and during the shifting of the valve air flows in a continuous manner from the pressure supply through passage 21, thereby providing a particularly effective blowing out of the particles of accumulated material loosened by the drill. The flow of air through the drill continues during the return stroke of the piston by virtue of the working pressure in the forward end of the bore 17.

It will be apparent from the foregoing description and explanation that the invention provides a device for opening the tell-tale holes of staybolts, which is characterized by numerous advantages. In the first place, the construction of the device is relatively simple and inexpensive. Its operation, furthermore, is based on tried principles so that maintenance problems are reduced to a minimum. The mass of the recipro-

cating drill is relatively small. The inertia of the drill is correspondingly reduced and the drill is capable of reciprocating at high speed. The ability to turn the drill relative to the gun is a great convenience to the operator as it is desirable to turn the drill yet it is not always convenient to turn the gun. The lever 43 is so made that it can readily be manipulated by the operator with his left hand, without danger of injury thereto by the vibration, since the wrench fits loosely on the drill head permitting axial movement of the latter relative thereto.

By leading the air for blowing out the chips through the piston and drill, I avoid any lateral connections to the latter which would be subject to breaking off because of the rapid reciprocation of the drill. The effectiveness of the successive puffs or jets of air in blowing out the detached particles of accumulated material has already been mentioned.

Although I have illustrated and described but a preferred embodiment of the invention, it will be apparent that changes in the construction and arrangement disclosed herein may be made without departing from the spirit of the invention or the scope of the appended claim. The piston 18, for example, may be solid instead of having the bore 47 therethrough. In that case, air flows through the drill passage 48 only during the return stroke of the piston when substantially full line pressure exists in the forward end of the bore 17. This produces an even more pronounced effect of separate puffs or jets of air than that obtained with a piston having a longitudinal bore therethrough.

I claim:

A device for removing accumulations from the tell-tale hole of a staybolt, comprising a barrel having a bore therethrough, a piston reciprocable in said bore, a valve controlling the admission of fluid under pressure to opposite ends of said bore from a pressure supply, whereby to reciprocate said piston, a drill in the end of said barrel so as to be subject to impact blows by said piston, and aligned, restricted axial passages through said piston and drill, there being a restricted port in direct communication with the rear end of the bore and the pressure supply, whereby the passage through the drill is continuously open to the pressure supply during the shifting of the valve to reverse the movement of the piston.

EDWARD S. FITZ SIMMONS.
